UNITED STATES PATENT OFFICE.

JOHN F. GODFREY, OF ELKHART, INDIANA.

HOIST MECHANISM.

1,397,164.

Specification of Letters Patent.

Patented Nov. 15, 1921.

Application filed August 23, 1920. Serial No. 405,450.

To all whom it may concern:

Be it known that I, JOHN F. GODFREY, a citizen of the United States, residing at Elkhart, in the county of Elkhart and State of Indiana, have invented certain new and useful Improvements in Hoist Mechanism, of which the following is a specification:

This invention relates to hoist mechanism which is capable of elevating and conveying 10 loads.

One object of the invention is to provide a simple, compact and efficient hoist which is capable of hoisting a load and simultaneously and independently conveying another load in either of a plurality of directions.

Another object is to provide a relatively inexpensive but durable hoist having its parts arranged and controlled in a manner 20 to meet the various requirements for successful commercial operation.

These and other objects are accomplished by means of the hoist mechanism disclosed on the accompanying sheets of drawings, in 25 which—

Figure 1 is a front elevation of hoist mechanism embodying my invention;

Fig. 2 is a top plan view of the same;

Fig. 3 is an end elevation of the same hoist 30 mechanism; and,

Fig. 4 is a detail side elevation showing the brake and release mechanism associated with clutch mechanism.

The various novel features of the invention 35 will be apparent from the following description and drawings and will be particularly pointed out in the appended claims.

Referring to the figures of the drawings, it 40 will be noted that I have disclosed hoist equipment mounted upon a suitable base 9, the hoist and conveying mechanism being operated by an electric motor 10 mounted upon the base 9. The shaft 11 of the electric motor has secured thereto a pinion 12 which 45 meshes with and drives a relatively large gear 13 mounted upon one end of a shaft 14, which carries concentrically with the gear 13 a smaller gear 15 which meshes with and drives a gear 16 mounted upon one end of a shaft 17. Also mounted upon the shaft 14 is a gear 18 which meshes with a gear 19 for driving the latter, said gear 19 being operatively connected to a drum 20 around which a cable may be wound for hoisting purposes.

Loosely mounted upon the shaft 14 near one end thereof is an outer clutch member 21

to which a gear 22 is secured, said gear 22 meshing with a relatively large gear 23 operatively connected to a conveying drum 24 around which a cable may be wound, said 60 conveying drum being positively driven in opposite or reverse directions by mechanism to be referred to hereinafter. Also loosely mounted upon the shaft 17 is another outer clutch member 25 to which is secured a gear 65

26 also meshing with the gear 23. It will be noted that in view of the fact that the gears 15 and 16 are in mesh with each other, shafts 14 and 17 are caused to rotate in opposite directions. Accordingly, gears 22 and 26, respectively, drive the gear 23, and accordingly the reverse traveling drum 24, in opposite directions. Also loosely mounted upon the shaft 14 is another outer clutch member 70

27 to which is secured the gear 18 for driving the hoisting drum 20 through gear 19. From the arrangement thus far described, it will be understood that when the motor is in operation the two driving shafts 14 and 17 will be in continuous operation. In this 80 particular hoist the internal clutch mechanism takes the form of expanding rings which normally spring out of engagement with the interior surface of the outer clutch members. For expanding the inner clutch 85 member for gripping outer clutch member 21, I have provided an ordinary type of operating member 28 having studs 29 which are engaged by a cone member 30 for expanding the inner clutch member and causing the reverse traveling drum 24 to travel in one direction through the operation of the outer clutch member 21 and gears 22 and 23.

In a similar manner the outer clutch member 90 25 may be driven for driving the reverse 95 traveling drum in an opposite direction through the operation of a cone member 31, and likewise the hoisting drum may be operated through the outer clutch member 27 through the operation of a cone member 32. 100 The reverse clutches are operative simultaneously so that when one clutch is thrown in for driving the traveling drum 24 in one direction, the other clutch is thrown out, there also being a central neutral inoperative position. This is accomplished by actuating the cone members 30 and 31 in opposite directions by a single control lever 33 which is pivotally connected at 34 to a supporting arm 35 secured to a frame member 110 36. The pivotal point 34 of the lever is between the cone-shaped members 30 and 31.

which are respectively slidably mounted upon the shafts 14 and 17 and accordingly it is impossible to attempt to drive the reverse traveling drum 24 in two directions at the same time. To control the operation of the hoisting drum 20 a control lever 37 is provided which actuates the cone member 32, which is slidably mounted upon the shaft 14, said control lever 37 being pivotally mounted at 38 on the supporting arm 35. From the arrangement thus far described, it is apparent that the hoisting drum may be operated whether or not the reverse traveling drum 24 is being operated, and likewise the reverse traveling drum may be operated in either direction whether or not the hoisting drum 20 is being operated. In other words, the hoisting and reverse traveling or conveying drums are capable of independent 20 operation and also may be operated at the same time independently of each other.

The hoisting drum is provided with brake mechanism, including a brake band 39, which passes around and engages the outer clutch member 27, one end of said brake band 39 being anchored at the point 40 to an upstanding arm 41 secured to the bed plate 9, the other end of the brake band 39 being connected through a spring or resilient member 42 to a member 43 pivotally connected at 44 to a foot brake pedal 45, one end of the latter of which is pivotally connected at a point 46 to a projecting portion 47 of the arm 41. It is apparent, therefore, that when pressure is applied at the outer or free end of the foot pedal 45, the brake band 39 will be forced into intimate contact with the outer clutch member 27 for retarding or stopping the movement of the hoisting drum. The brake pedal 45 may be locked in any braking position through the operation of a pawl 48 pivotally connected at 49 to upstanding ears 50 on the pedal 45, said pawl having a plurality of teeth 51, any one of which may engage under a lip 52 formed on a portion 53 of the arm or casting 41. The pawl may be released by depressing the free end 54 thereof. Similarly the reverse traveling drum 24 may be retarded or stopped by a brake including a brake band 55 embracing the outer clutch member 25, one end of the brake band being anchored at the point 56 to an arm 57 secured to the bed plate 9 and the other end of the brake band 55 being yieldably connected to a foot pedal 58 through a connection 59. The brake may be locked in a braking position by means of a pawl 60, the teeth 61 of which coöperate with the lip 62 at the outer end of the arm 57, said pawl being pivotally mounted at 63 to upstanding ears 64 on the pedal 58. The pawl may be released by applying pressure to the foot portion 65 thereof.

65 Preferably the operating shafts 14 and

17 are rotatably mounted and supported in bearings carried by the oppositely arranged side frames 36 and 66 which are secured to the bed plate 9 in any suitable manner. Likewise the stationary shaft 67 which supports the hoisting drum 20 and reverse traveling drum 24 is mounted in the side frames 36 and 66. In this connection it will be appreciated that the drums 20 and 24 are loosely mounted on the supporting shaft 67, 75 and in this arrangement are spaced from each other by a suitable spacing member 68. These drums 20 and 24 are located inwardly from the side frames 36 and 26 between their associated gears 19 and 23. 80

This arrangement of parts and the control thereof provide hoisting mechanism which is simple, compact, durable and efficient and which is adapted to meet all of the requirements for successful use. 85

It is my intention to cover all modifications of the invention falling within the spirit and scope of the following claims.

I claim:

1. In hoist mechanism, two side frames, 90 three shafts supported by said side frames and extending therebetween, a hoisting drum and a reverse motion drum independently mounted on one of said shafts, gearing mechanism carried by said other two shafts 95 for operating said hoisting and reverse motion drums, and brake mechanism operating upon said gearing mechanism associated with each drum.

2. In a hoist mechanism, spaced shaft 100 supporting means, a single drum-carrying shaft extending therebetween, two drums independently mounted on said shaft, a gear fixedly associated with each drum and carried by the end of the drum adjacent the 105 shaft supporting means, and means adapted to selectively drive one drum in either direction and simultaneously to drive the other drum in a single direction.

3. In a hoist mechanism, spaced shaft supporting means, a single drum-carrying shaft extending therebetween, two drums independently mounted on said shaft in fixed axial relation, a gear fixedly associated with each drum and carried by the end of the 115 drum adjacent the shaft supporting means, a pair of shafts extending parallel to said drum shaft and provided with gears adapted to selectively drive one drum in either direction and simultaneously to drive the other 120 drum in a single direction, said drives being independently controlled by clutches, and brakes associated with the driving means of each drum.

4. In a hoist mechanism, shaft supporting means, a single drum-carrying shaft supported thereby, a hoisting drum and a conveying drum independently mounted on said shaft in fixed axial relation, a gear shaft adjacent said drum-carrying shaft 125 130

- carrying gears adapted to drive each of said drums independently of each other, and a second gear shaft carrying a gear adapted to drive said conveying drum in the opposite direction independently of the motion of the hoist drum.
5. In a hoist mechanism, shaft supporting means, a single drum-carrying shaft supported thereby, a hoisting drum and a conveying drum independently mounted on said shaft, a gear shaft adjacent said drum-carrying shaft carrying gears adapted to drive each of said drums independently of each other, and a second gear shaft carrying a gear adapted to drive said conveying drum in the opposite direction, and brakes operating upon the driving gears of each of said drums.
6. In a hoist mechanism, shaft supporting means, a single drum-carrying shaft supported thereby, a hoisting drum and a conveying drum independently mounted on said shaft, a driven gear shaft adjacent said drum-carrying shaft, driving gears loosely mounted on said gear shaft in mesh with gears connected to each of said drums, an independent clutch associated with each said driving gear, a second gear carrying shaft driven in the reverse direction from said first gear carrying shaft, a reverse driving gear for said conveying drum loosely mounted on said second gear carrying shaft, and a clutch adapted to connect said last-named gear to its shaft.
7. In a hoist mechanism, shaft supporting means, a single drum-carrying shaft supported thereby, a hoisting drum and a conveying drum independently mounted on said shaft, a driven gear shaft adjacent said drum-carrying shaft, driving gears loosely mounted on said gear shaft in mesh with gears associated with each of said drums, an independent clutch associated with each said driving gear, a second gear carrying shaft driven in the reverse direction from said first gear carrying shaft, a reverse driving gear for said conveying drum loosely mounted on said second gear carrying shaft, a clutch adapted to connect said last-named gear to its shaft, and a single operating lever for both clutches for the drive gears for the conveying drum.
8. In a hoist mechanism, shaft supporting means, a single drum-carrying shaft supported thereby, a hoisting drum and a conveying drum independently mounted on said shaft, a driven gear shaft adjacent said drum-carrying shaft, driving gears loosely mounted on said gear shaft in mesh with gears associated with each of said drums, an independent clutch associated with each said driving gear, a second gear carrying shaft driven in the reverse direction from said first gear carrying shaft, a reverse driving gear for said conveying drum loosely mounted on said second gear carrying shaft, a clutch adapted to connect said last-named gear to its shaft, and a single operating lever for both clutches for the drive gears for the conveying drum.
9. In a hoist mechanism, shaft supporting means, a single drum-carrying shaft supported thereby, a hoisting drum and a conveying drum independently mounted on said shaft, a driven gear shaft adjacent said drum-carrying shaft, driving gears loosely mounted on said gear shaft in mesh with gears associated with each of said drums, an independent clutch associated with each said driving gear, a second gear carrying shaft driven in the reverse direction from said first gear carrying shaft, a reverse driving gear for said conveying drum loosely mounted on said second gear carrying shaft, a clutch adapted to connect said last-named gear to its shaft, and a single operating lever for both clutches for the drive gears for the conveying drum, said lever being so supported as to prevent simultaneous operation of both clutches.

Signed at Elkhart, Indiana, this 19th day of August, 1920.

JOHN F. GODFREY.
